UNITED STATES PATENT OFFICE

JOE HENRY NICKS AND ELERY EDWARD MOSHER, OF REFUGIO, TEXAS

BLOW-OUT PREVENTER ATTACHMENT

Application filed December 10, 1930. Serial No. 501,420.

This invention relates generally to an improvement in blow out preventer attachments, adapted to lock the rams of a standard blow out preventer head.

5 The object of this invention is to provide a device of this kind, whereby the rams may be quickly actuated and locked in well pressure resisting position during the blow out of the well, whereby to eliminate the slow and dangerous process of manual manipulation, and to provide the further advantages which will be recognized herein.

This and other objects and advantages, the nature of the invention, and its composition and arrangement and combination of parts will be readily understood by any one acquainted with the art to which this invention relates upon consulting the following description of the drawings, in which:—

20 Figure 1 is a general side elevational view showing an embodiment of our invention associated with the blow out preventer structure.

25 Figure 2 is a partial longitudinal vertical sectional view through Figure 1.

Figure 3 is a similar view showing the ram in the inward, blow out preventing position.

30 Figure 4 is a view similar to Figure 3 showing the ram locked in said position.

Figure 5 is an enlarged longitudinal vertical sectional view through one of the members of our improved attachment disclosing the disposition of parts and their construction.

35 Figure 6 is a detailed view of the housing of the attachment.

Figure 7 is a transverse vertical sectional view taken approximately on the line 7—7 of Figure 6.

40 Referring in detail to the drawings the numeral 5 designates generally the well head blow-out preventer structure, the numeral 6 the tool projecting through the said structure, the numeral 7 the pipe system for conducting the fluid from an associated pump for actuating the rams of the blow-out preventer.

45 The numeral 8 designates generally one of the attachments of the invention which comprises the annular adapter 9 which is adapted

to screw-thread at 10 into the preventer structure 5 as shown. The adapter is formed with a collar 11 which has a tapered screw threaded bore 12 for receiving the tapered nipple 13 on the associated end of the locking housing 14 of our attachment. Referring to Figures 5 and 6, it will be seen that the housing 14 consists of a cylindrical body comprising a plain outer end 15 an inner end 16 on which the tapered nipple 13 is formed. The ends 55 15 and 16 are connected by upper and lower longitudinal members 17 and 18 having the cross section disclosed in Figure 7. The end 15 has a longitudinal bore 19 and the end portion 16 has a longitudinal bore 20 in alignment with the bore 19. Also in alignment with the bore 20 is an enlarged recess 21 opening inwardly of the end portion 16. The stem 22 has an annular groove 23 at its inward end for rotatable connection with the ram 24. 60 From the point indicated at 23 to an intermediate portion of the stem, it is smooth to enable it to slide in the bore 20 in a snug manner and to be properly packed by a series 65 of packing rings 25 maintained in proper adjustment by an adjusting nut 26 screw threaded as at 27 in the recess 21. From said intermediate point to the outer end portion of the stem 22 it is screw threaded as at 28, and the outer extremity beyond the screw threaded 70 portion 28 is formed to receive a wrench or crank, or other operating lever, as at 29. The bore 19 in the outer end of the housing 14 is sufficiently large to permit free sliding of a lock sleeve designated 30 which is screw 75 threaded on the screw threaded portion 28 of the stem 22. The lock nut sleeve 30 is externally screw threaded at 31 to provide for the mounting thereon of a lock nut 32. The lock nut 32 is placed on the sleeve 30 outwardly of the outer end portion 15 of the housing 14. On the inner end of the sleeve 30 disposed within the housing is an annular shoulder 33 adapted to be abutted against the inner face of the end portion 15 as will subsequently be described. It should be noted that the bore 19 is not threaded, but is smooth. 80

85 In Figure 2 is shown the completely withdrawn position of the ram 24, whereas in Figure 3 is shown the fully inward position 90

100

of the said ram. Figure 4 discloses the ram in the said fully inward position, and in addition the locking sleeve 30 with its shoulder 33 abutted against the inner face of the end 5 portion 15 of the housing, and the lock nut 32 forcibly engaged against the outer face of the said portion 15 of the housing, so that the locking sleeve 30 is locked against movement in either direction. Since the stem 22 10 by being threaded in the locking sleeve is positively prevented from movement in either direction relative to the locking sleeve, the consequence is that the ram 24 is then securely locked in the full inward position. 15 Under working conditions a slush pump is used to force fluid under pressure through the pipes 7 and the duct 34, against the back of the ram in the preventer housing, so that with the locking sleeve and the lock nut in 20 the positions shown in Figures 2 and 3, the ram 24 carrying the stem 22 moves inwardly through the bores 19 and 20. When the ram has in this manner been moved to its extreme inward position, disclosed in Figures 25 3 and 4, the locking sleeve, easily accessible for manipulation because of the open formation of the housing 8, the shoulder 33 of the locking sleeve being formed hexagonal or in any other suitable form, may be quickly 30 reached and gripped by a suitable tool and rotated upon the stem into forcible engagement with the inner face of the end portion 15 of the housing, whereupon the lock nut 32 is rotated on the said locking sleeve from the 35 position shown in dotted lines at 32a in Figure 4 to the locking position in forcible engagement with the outer face of the portion 15 of the housing 14. With this adjustment of the parts of our appurtenance, the ram is 40 positively and forcibly locked against displacement from its fully inward position, and the tool 6 is effectively prevented from being blown out of the well.

It will be observed that the comparatively 45 few and easy operations required for manipulating the rams as described above enable applying and locking the rams so quickly that the dangers and losses consequent upon a slow and ineffective manipulation of 50 the rams are prevented and the sand, oil, and water forced from the well during a "blow" are not given a chance to blow out the packings of the rams and render the blow out preventer useless. It is believed also to 55 be obvious that our device is a simple one, cheap to manufacture and extraordinarily effective and rugged and otherwise admirably adapted for the purposes for which it is designed.

60 It is to be definitely understood that we do not desire to limit the application of this invention to the particular modification set out herein to illustrate the principles thereof, and any change or changes may be made 65 in material, structure, or combination of

parts, within the spirit and scope of the invention and the subjoined claims.

What is claimed as new is:—

1. A blow out preventer locking structure of the type described comprising a rotatable 70 ram stem slidable through a housing mounted on the preventer having its outward end portion screw threaded and its inward end portion smooth and packed in the housing, a shouldered locking sleeve mounted screw 75 threadedly on the outward end portion of the stem, and a lock nut screw threaded upon the locking sleeve, said locking sleeve and said lock nut adapted to engage portions of the housing to lock the stem against longitudinal movement in the housing and lock the ram in its position. 80

2. A locking structure of the type described for a blow out preventer comprising a housing mountable on the preventer, a ram stem connected to the ram of the preventer and slidable in the housing, fluid pressure means for initially actuating said ram, and means for locking said ram against return movement comprising a locking sleeve screw 90 threaded on the outer end portion of the sleeve having a shoulder for abutting an inner portion of the housing, a lock nut on said sleeve for abutting an outer portion of the housing for locking said sleeve against 95 movement. 100

3. An attachment for a blow-out preventer head, comprising a housing adapted to be mounted thereon, a stem slidable in the housing and rotatably connected with a ram 105 of the preventer head, rotatable and slidable means adapted to be moved into a position in which it cooperates with a portion of the housing and the stem whereby the stem can be moved longitudinally only by rotating it. 110

4. An attachment for a blow-out preventer head, comprising a housing adapted to be mounted thereon, a stem slidable in the housing and rotatably connected with a ram 115 of the preventer head, rotatable and slidable means adapted to be moved into a position in which it cooperates with a portion of the housing and the stem whereby the stem can be moved longitudinally only by rotating it, said means being capable of being initially 120 positioned with respect to the housing so as not to prevent sliding and rotary movement of the stem, said means being capable of being subsequently moved into such a relation with the housing that the stem is locked against sliding and rotary movement and can then be moved longitudinally only by rotating it. 125

5. An attachment for a blow-out preventer head, comprising a housing adapted to be mounted thereon, a stem slidable in the housing and rotatably connected with a ram of the preventer head, slidable and rotatable means adapted to be moved into a position in which it cooperates with a portion of the housing 130 and the stem whereby the stem can be moved

longitudinally only by rotating it, said means being capable of being initially positioned with respect to the housing so as not to prevent sliding and rotary movement of the stem,
5 said means being capable of being subsequently moved into such a relation with the housing that the stem is locked against sliding and rotary movement and can then be moved longitudinally only by rotating it, said means
10 being also capable of being arranged with respect to the stem and the housing so that the stem is permitted free rotary movement, while permitted longitudinal sliding movement in one direction only.

15 In testimony whereof we affix our signatures.

JOE HENRY NICKS.
ELERY EDWARD MOSHER.
